STEAM AND SPRAY IRON

Donal F. Fitzgerald, Winsted, Conn., assignor to Son-Chief Electrics, Inc., Winsted, Conn., a corporation of Connecticut

Filed Oct. 26, 1967, Ser. No. 9,180

Term of patent 14 years

(Cl. D49—6)

FIG. 3.

FIG. 4.

FIG. 5.

FIG. 6.

FIG. 7.

FIGURE 1 is a side elevation of a steam and spray iron showing my new design.

FIGURE 2 is a top plan view of the steam and spray iron shown in FIGURE 1.

FIGURE 3 is a front elevation of the steam and spray iron shown in FIGURE 1.

FIGURE 4 is a rear elevation of the steam and spray iron shown in FIGURE 1.

FIGURE 5 is a diagrammatic cross section taken on the line 5-5 of FIGURE 1.

FIGURE 6 is a diagrammatic cross section taken on the line 6-6 of FIGURE 1.

FIGURE 7 is a diagrammatic cross section taken on the line 7-7 of FIGURE 1.

FIGURE 8 is a side elevation of the opposite side of the steam and spray iron shown in FIGURE 1.

The characteristic feature of my design reside in the portions shown in full lines as shown, it being understood, however, that the broken line disclosure constitutes a part of the claim.

I claim:

The ornamental design for a steam and spray iron, substantially as shown and described.
